UNITED STATES PATENT OFFICE.

ARTHUR H. ANDREWS, OF BROOKLYN, NEW YORK.

DRAFTING DEVICE.

No. 830,282.

Specification of Letters Patent.

Patented Sept. 4, 1906.

Application filed December 31, 1904. Serial No. 239,208.

To all whom it may concern:

Be it known that I, ARTHUR H. ANDREWS, a citizen of the United States, residing at Brooklyn, in the county of Kings and State 5 of New York, have invented certain new and useful Improvements in Drafting Devices, of which the following is a specification.

The purpose of my invention is to provide a device for saving time and labor in drafting 10 and which is also found useful for giving instructions in drawing.

In the accompanying drawings, Figure 1 is a perspective view of the device provided with raised or embossed ridges in parallel 15 lines and suitable for making section-lines or hatched work on tracing paper or cloth. Fig. 2 is a section taken diagonally through the card shown in Fig. 1, at right angles to the parallel ridges and on an enlarged scale. Fig. 20 3 is a detail perspective view of the end of the handle which engages the card. Fig. 4 is a plan view of a drawing-board having drawing-paper and tracing paper or cloth thereon and illustrating the manner of using the device 25 shown in Fig. 1. Figs. 5, 6, 7, and 8 are perspective views of cards having differently-embossed surfaces suitable for representing various materials on the tracing paper or cloth. Fig. 9 is a side view of part of a pen-30 cil having a beveled lead suitable for rubbing over the tracing paper or cloth above the embossed parts of the card.

Referring to Figs. 1 to 4, inclusive, of the drawings, A indicates a card or plate which 35 may be of metal, fiber, wood, or any suitable material, but which is preferably made of stiff parchmentized paper or celluloid and is preferably translucent or transparent and somewhat flexible. On the upper surface of 40 the card or plate shown in Figs. 1 and 2 are formed a series of parallel ridges a, preferably running at an angle of forty-five degrees to the edges of the plate, the plate in the drawings being rectangular. When the card or 45 plate is made of parchmentized paper, celluloid, or other thin sheet material which may be embossed, the ridges or raised portion a may be formed by embossing the card, so that it will present a corrugated surface having 50 the ridges a of uniform height and uniform distances apart. Narrow slots a' are cut in the card parallel with its edges and adjacent thereto, and these slots are adapted to receive the flat offset end b of a handle B. 55 This handle may be made of any suitable

thin material, such as parchmentized paper, celluloid, or metal. When the end b is inserted through one of the slots a, the shoulder b' extends vertically through the slot and the handle interlocks with the card, so that 60 the card may be lifted or moved forward or backward by the handle.

If desired, the handle may be attached permanently to the card; but preferably it is removably connected, so that the card may 65 be used without the handle, or the latter may be connected to the different edges of the card.

In Fig. 4 I have illustrated the manner of using the card shown in Fig. 2 for rapidly 70 forming section-lines upon tracing paper or cloth. In said figure, C indicates a drawing-board, D indicates a sheet of drawing-paper, and E indicates a sheet of tracing paper or cloth held upon the drawing-paper by thumb-tacks F in the usual manner. Upon the tracing paper or cloth a drawing G is shown, which has been traced through from the drawing paper with the exception of the part surrounding the circle 1 and within the lines 2, 75 3, 4, and 5, which part it is desired to show in section. Instead of drawing these section-lines with a pen and ruler in the usual way the card or plate A, as indicated in dotted lines in Fig. 4, is inserted between the tracing 80 paper or cloth and the drawing-paper by means of the handle B and located so that the corrugations or ridges on the card will be directly beneath the part on the tracing paper or cloth where it is desired to form the 85 section-lines. This, as will be seen, is accomplished without necessitating the removal of the thumb-tacks F.

When the card is in position, an ordinary 90 lead-pencil having a lead of medium softness 95 is rubbed over the area on which it is desired to form the section-lines, and the lead-pencil lines are thus formed on the tracing paper or cloth, following the lines of the ridges on the card. A lead-pencil L, Fig. 9, having a thick 100 lead beveled at the end, as indicated by the reference-letter l, to afford sufficient surface is found most convenient for this purpose. In Fig. 4 the full lines g in the upper left-hand portion of the area bounded by the rectangle 105 2 3 4 5 indicate lines formed by rubbing the pencil over the tracing paper or cloth while the remainder of the area is unfinished, the dotted lines indicating the ridges on the card beneath the tracing-paper. By rubbing the 110

pencil over the entire area to be sectioned lines g will be formed throughout the area on the tracing paper or cloth.

- The cards are prepared in sets having embossed lines or portions to correspond with various conventional designs, symbols, or fillings employed in the draftsman's art to indicate upon drawings sections, materials, colors, and the like. Thus in Fig. 5 the card A¹ has alternately continuous and broken embossed lines a^3 and a^4 , representing the usual section-lines for a vitreous substance, such as glass. In Fig. 6 the card A² has a series of parallel broken lines a^5 , representing cement. In Fig. 7 the card A³ has irregularly-embossed outlines a^6 , which may represent earth or other material, and in Fig. 8 the card A⁴ has embossed lines a^7 , running at right angles to one another and representing wire or cloth fabric. These cards are employed in the manner illustrated in Fig. 4, and the sets may include cards having embossed surfaces to represent a large variety of materials, colors, and sections.
- For tracings where considerable section work is to be done and for rough work—such as concrete, stone, earth, &c.—a great deal of time may be saved in the drafting-room by the use of these cards, which of course may be of any suitable size for the work. When cards of semitransparent parchmentized paper or cards of celluloid are used, the drawing beneath the card may be seen and omissions in the outline on the tracing supplied while the card is still in position.

What I claim, and desire to secure by Letters Patent, is—

1. A device for assisting in drafting comprising a thin hard card having embossed portions or areas of uniform height, which when the card is placed beneath tracing cloth or paper and the latter rubbed with a pencil, will cause the production on the tracing cloth or paper of a conventional symbol or filling used in the draftsman's art.
2. A device for assisting in drafting comprising a card of parchmentized paper having embossed portions or areas of uniform height, which when the card is placed beneath tracing cloth or paper and the latter rubbed with a pencil, will cause the production on the tracing cloth or paper of a conventional symbol or filling used in the draftsman's art.
3. A device for assisting in drafting comprising a thin hard card having embossed

portions or areas of uniform height, which when the card is placed beneath tracing cloth or paper and the latter rubbed with a pencil, will cause the production on the tracing cloth or paper of a conventional symbol or filling used in the draftsman's art to represent a color or substance.

4. A device for assisting in drafting comprising a thin hard card or plate having embossed portions or areas of uniform height, which when the card is placed beneath tracing cloth or paper and the latter rubbed with a pencil, will cause the production on the tracing cloth or paper of a conventional symbol or filling used in the draftsman's art to represent a substance.

5. A device for assisting in drafting comprising a thin hard card or plate having embossed portions or areas of uniform height, which when the card is placed beneath tracing cloth or paper and the latter rubbed with a pencil will cause the production on the tracing cloth or paper of a conventional symbol or filling used in the draftsman's art, said device having one or more slots in its margin for the attachment of a handle.

6. A device for assisting in drafting comprising a thin hard card or plate having embossed portions or areas of uniform height, which when the card is placed beneath tracing cloth or paper and the latter rubbed with a pencil, will cause the production on the tracing cloth or paper of a conventional symbol or filling used in the draftsman's art, said device having one or more slots in its margin for the attachment of a handle, and a handle having a flattened offset portion adapted to fit into said slots.

7. A drafting implement for engineers, architects, &c., comprising a series of thin hard cards or plates each having embossed portions or areas thereon, which when the card is placed beneath tracing-paper or tracing-cloth and the latter rubbed with a pencil, will cause the production on the tracing cloth or paper of a conventional symbol or filling used in the draftsman's art, the various cards in the set being differently embossed, so as to produce different symbols or fillings.

In testimony whereof I affix my signature in presence of two witnesses.

ARTHUR H. ANDREWS.
